Primary Examiner — Caron D Veynar*Assistant Examiner* — Martie K Holtje(74) *Attorney, Agent, or Firm* — Conley Rose, P.C.; J. Robert Brown, Jr.**CLAIM**

The ornamental design for an HVAC cover, as shown and described.

DESCRIPTION

FIG. 1 is a top, right perspective view of an HVAC cover showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is a bottom, left perspective view thereof.

The portions of the HVAC cover depicted by means of broken lines are shown for the purpose of illustrating environmental structure that forms no part of the claimed design.

1 Claim, 6 Drawing Sheets(56)
